[57] CLAIM

The ornamental design for a suspender fastener, as
shown and described.

DESCRIPTION

FIG. 1 is a top plan view of a suspender fastener showing
my new design;

FIG. 2 is a left side elevational view thereof;

FIG. 3 is a right side elevational view thereof;

FIG. 4 is a bottom plan view of a suspender fastener
depicting my new design;

FIG. 5 is a front elevational view of the suspender fas-
tener depicted in FIG. 1; and

FIG. 6 is a sectional view of the suspender fastener
depicted in FIG. 1 taken along the center line.
